LEAD EXTRUSION APPARATUS

Aeneas J. N. Duclos, South Orange, N. J., assignor
to Western Electric Company, Incorporated,
New York, N. Y., a corporation of New York

Application March 26, 1936, Serial No. 70,909

7 Claims. (Cl. 207—16)

This invention relates to lead extrusion apparatus, and more particularly to heating means for the die block of lead extrusion apparatus.

An object of the invention is to provide an effective and efficient heating means for the die block of lead extrusion apparatus.

In accordance with one embodiment of the invention, a single burner is provided to cooperate with a shield to guide the heat around the die block from the exit end of the cable to be sheathed toward the entrance end of the cable.

Other objects and advantages will appear as the description proceeds.

A complete understanding of the invention may be had by reference to the following description taken in conjunction with the accompanying drawing, in which

Fig. 1 is a front elevation of an apparatus embodying the invention;

Fig. 2 is a sectional view taken on line 2—2 of Fig. 1;

Fig. 3 is a fragmentary view of a support for the shield, and

Fig. 4 is a sectional view taken on line 4—4 of Fig. 3.

The invention is illustrated as applied to a conventional type of lead extrusion apparatus having a cylinder 5 which is filled with molten lead. After the lead has solidified and reached a certain degree of plasticity in the cylinder, pressure is exerted on the lead by means of a relatively movable ram 6 to force the lead through a die block 7 and cover a cable 8 with a lead sheath 9. The uncovered cable is fed through an aperture in an adjusting nut 11 for the core tube and issues with a lead sheathing through an aperture in the adjusting nut 12 for the extrusion die.

In sheathing a cable it usually requires more than one cylinder-full of lead to cover a cable, and when one cylinder-full of material has been extruded the ram is withdrawn and the cylinder is refilled. Since a considerable amount of lead remains in the die block, after the cylinder has been emptied it is evident that the lead in the die block will solidify to too great an extent during the refilling and subsequent cooling of the new charge in the cylinder. This results in numerous operating difficulties among which may be mentioned the excessive pressure required to extrude the lead from the die block, and the improper welding of the lead sheath at the seam on the underside of the sheath. Means must, therefore, be provided to maintain the lead in the die block at the proper temperature at all times. It has been found that a greater amount

of heat should be applied at that end of the die block where the sheathed cable leaves the die block. This is accomplished in the present invention by providing a pair of shields 13 which are arcuately shaped to conform to the periphery of the die block. Each of these shields comprises an inner sheet of a heat resistant metal 14 and an outer sheet 15 of similar material between which is interposed a layer of heat insulating material such as asbestos. The forward end of this shield is provided with an end member 17 which does not extend downwardly as far as the shield, and is provided with an aperture 18 through which a burner 19 extends to direct a flame against the die block. Another end member 21 is provided at the rearward end of the shield and is similar to the end member 17 except that it is not provided with an aperture for a burner. The end members 21 are pivotally mounted on the shields 13 and serve to control the temperature in the spaces between the shields and the die block.

The shields rest upon an annular support formed by a pair of semi-circular members 25 through which a plurality of bolts 26 extend whose heads engage a cylindrical portion of the apparatus. Each of these bolts is provided with sleeves 27 and between the sleeves an arcuate member 28 is supported. A flat arcuate member 29 rests upon each of the sleeves of the bolts and the ends of the arcuate members 29 are provided with eyelets surrounding the sleeves of the end bolts. Since die blocks of different sizes are sometimes used in the apparatus the shields may be placed on either the inner or outer arcuate members 29 to position them for the particular size of die block being used. For convenience in shifting the shields a pair of handles 30 is provided through which a bar may be passed to lift the shields from one position to another.

The shields may also be adjusted vertically by 40 vertically adjusting the annular support upon which they rest.

The burner 19 is mounted upon a pair of upright arms 33 carried by a weighted block 34 which may be positioned in any desired location 45 on the ledge 35 adjacent the die block. The burner may be clamped to the upright arms by means of a clamping plate 36 secured in place by bolts and wing nuts to permit convenient vertical adjustment of the burner. The burner is supplied with a combustible gas mixture through a flexible tube 37. Valves 38 are provided so that the amount of gas and thereby the size of the flame may be individually controlled for each of the burners. A pilot burner 39 may also be pro- 55

vided to ignite or maintain the flame of the main burner.

As shown more clearly in Fig. 2 of the drawing, the flame is directed against the die block adjacent the exit end of the cable and, therefore, the maximum amount of heat will be communicated to the die block at this point. The angle at which the flame strikes the die block together with the shield causes heat to travel around the die block, and since a large portion of the heat is absorbed by the die block at the point of application of the flame, the amount of heat applied to the die block will progressively decrease toward the entrance end of the cable. The die block is preferably provided with thermocouples 41 as an aid to the operator in maintaining the proper temperature in the die block. If the temperature of the material in the die block becomes too high, the member 21 may be swung outwardly away from the die block to decrease the concentration of heat in the space between the shield and the die block or the amount of the combustible gas supplied to the burner may be varied. In this manner a very effective and accurate control of the temperature of the die block may be obtained to provide a uniform sheath of high quality.

In order to assist the operator to direct the flame to the proper area of the die block, a target 42 is provided on the die block and consists preferably of an area coated with aluminum painted or sprayed thereon.

It will be understood that the nature and embodiment of the invention herein disclosed is merely illustrative, and that many changes and modifications may be made therein without departing from the spirit and scope of the invention.

What is claimed is:

- 40 1. In a lead extrusion apparatus having a die block, a shield extending around a portion of said die block, end members extending from the ends of the shield to the die block leaving a space for the escape of gases, and means for projecting 45 heat through one of said end members into the space between the shield and the die block.
2. In a lead extrusion apparatus having a die

block through which a cable to be sheathed with lead is passed, a burner adjacent the exit end of the cable for directing a flame in the direction of the entrance end of the cable, and a shield for guiding the heat from the burner toward said entrance end. 5

3. In a lead extrusion apparatus having a die block through which a cable to be sheathed with lead is passed, a burner on either side of the exit end of the cable for directing flames around the die block toward the entrance end of the cable, and a shield for each burner for guiding the heat from the burner toward said entrance end. 10

4. In a lead extrusion apparatus having a die block through which a cable to be sheathed is passed, a shield extending over a portion of the die block between the exit and entrance points of the cable, and means for applying a progressively higher temperature toward the exit point 20 of the cable.

5. In a lead extrusion apparatus having a die block through which a cable to be sheathed is passed, a shield extending over a portion of the die block between the exit and entrance points 25 of the cable, and a single burner cooperating with said shield for applying a progressively higher temperature toward the exit end of the cable.

6. In a lead extrusion apparatus having a die block through which a cable to be sheathed with lead is passed, a shield circumferentially extending around a portion of the die block, an end member extending from the shield to the die block having an aperture therein, a burner for 35 projecting a flame through said aperture, and a second end member pivotally mounted on the opposite end of the shield.

7. In a lead extrusion apparatus, a burner, a shield cooperating therewith to apply heat to 40 the apparatus, and a support for said shield mounted adjacent to the apparatus comprising a plurality of annular members spaced progressively from the apparatus for selectively positioning the shield to regulate the application of 45 heat to the apparatus.
